F/G. 1

FIG. 2

FIG. 1 is a right front perspective view of a utility van, with the outer doors opened to reveal an illustrative arrangement of externally accessible compartments, including drawers, several of the latter being shown open for illustrative purposes, said compartments being suitable for holding tools and equipment such as might be carried by repairmen, contractors and the like;

FIG. 2 is a rear elevational view thereof;

FIG. 3 is a top sectional plan view thereof taken along the line 3—3 of FIG. 2; and

FIG. 4 is a left front perspective view thereof.

I claim:

The ornamental design for a utility van having externally accessible compartments, as shown and described.
